UNITED STATES PATENT OFFICE.

FRANCIS R. McKENNA, OF PROVIDENCE, RHODE ISLAND, ASSIGNOR TO BOURN RUBBER CO., OF PROVIDENCE, RHODE ISLAND, A CORPORATION OF RHODE ISLAND.

DESIGN FOR A SOLE OF SHOE.

No. 39,747.

Specification for Design.

Patented Jan. 5, 1909.

Application filed October 19, 1908. Serial No. 458,575. Term of patent 14 years.

To all whom it may concern:

Be it known that I, FRANCIS R. McKENNA, a citizen of the United States, residing at Providence, in the county of Providence and State of Rhode Island, have invented a new, original, and ornamental Design for the Sole of a Shoe, reference being had to the accompanying drawing.

The figure in the drawing represents a sole of a shoe, showing my design.

I claim—

The ornamental design for the sole of a shoe, as shown.

FRANCIS R. McKENNA.
